UNITED STATES PATENT OFFICE.

SERRIL W. NICHOLAS, OF PROVIDENCE, RHODE ISLAND, ASSIGNOR TO LEONARD-ROOKE COMPANY, OF PROVIDENCE, RHODE ISLAND, A CORPORATION OF RHODE ISLAND.

DESIGN FOR A HANDLE FOR A THERMOSTATIC VALVE.

Application filed September 25, 1926. Serial No. 19,176. Term of patent 14 years.

To all whom it may concern:

Be it known that I, SERRIL W. NICHOLAS, a citizen of the United States of America, residing at Providence, county of Providence, State of Rhode Island, have invented a new, original, and ornamental Design for a Handle for a Thermostatic Valve, of which the following is a specification, reference being had to the accompanying drawing, forming a part thereof.

Figure 1 is a top plan view and Figure 2 is a side elevation of a handle for a thermostatic valve, illustrating my new design.

I claim:

The ornamental design for a handle for a thermostatic valve, substantially as shown.

SERRIL W. NICHOLAS.
